UNITED STATES PATENT OFFICE.

CHARLES W. REINOEHL AND BENT L. WEAVER, OF STEELTON, PENNSYLVANIA.

GUARD-RAIL.

No. 925,226.

Specification of Letters Patent.

Patented June 15, 1909.

Application filed February 4, 1908. Serial No. 414,260.

To all whom it may concern:

Be it known that we, CHARLES W. REINOEHL and BENT L. WEAVER, citizens of the United States, and residents of Steelton, 5 Dauphin county, State of Pennsylvania, have invented certain new and useful Improvements in Guard-Rails, of which the following is a full, clear, and exact description, reference being had to the accompanying 10 drawings, of which—

Figure 1 is a plan view of a stock rail and guard rail showing our invention applied thereto. Fig. 2 is a section on the line $x-x$, of Fig. 1. Fig. 3 is a side view of the guard 15 rail.

This invention relates to improvements in guard rails, the object being to provide a guard rail with a renewable hard metal upper surface without cutting away any of the 20 stock portions of the guard rail; also, to provide means whereby, as the upper surface becomes worn, it may be adjusted to take up such wear.

To these ends the invention consists in providing the construction hereinafter fully described.

1 is a main rail, and 2 the guard rail adjacent thereto. The said guard rail 2, for a distance within which the wear takes place, 30 as between the points 3 and 4, is bent outwardly, as seen in Fig. 1, in a suitable bending apparatus. That is, said portion of the guard rail is bent outwardly to such abnormal extent that a wear piece 5, preferably of 35 hard and tough metal, and of some lateral thickness, may be secured on the inner side thereof, and its head portion 6, in line with the head portion of the guard rail, being a suitable distance from the opposite face of 40 the main rail. Said wear piece 5, being fitted to the guard rail and constituting, as it were, an inner extension thereof, is provided with a downwardly extending web portion 7, which is secured to the guard rail by means of 45 suitable bolts 8. As the outward bends in the guard rail at the points 3 and 4 are somewhat abrupt, they form shoulders against which the ends of the piece 5 abut, thereby preventing longitudinal movement of the 50 latter.

On the outer face of the guard rail we would usually secure one or more shims, 9, of sheet metal or the like, that fit the rail throughout a distance corresponding with

that of said wear piece; so that if and when 55 the inner face 5^a of the wear piece 5 becomes worn by passing wheel flanges, said wear may be taken up by withdrawing the bolts 8 and inserting a shim or shims 9 between the guard rail and the wear piece, and again 60 clamping the bolts 8 in place. We further remark that it is obvious that by the construction shown, the wear piece may be readily renewed when desired for any purpose, without removing the guard rail from 65 its place in the track.

It will be observed that by our invention, the wear piece 5 constituting an inward extension and consequent inward broadening, in effect, of the head of the guard rail, makes 70 it unnecessary for any portion of the foot flange 10 of the guard rail to be cut away, as is usually done in ordinary guard rails, in order to bring the inner side of the head thereof close enough to the opposite side of the head 75 of the main rail. Also, it is unnecessary, in our construction, to cut away any portion of the head of the guard rail, to accommodate the wear piece.

Having thus described our invention, we 80 claim as new and desire to secure by Letters Patent:—

1. A guard rail comprising a regular rail provided with a base, a vertical web and a head having equal dimensions on each side of its vertical center in cross section throughout its length, a wear piece arranged against the side of the head of said regular rail toward the main rail and provided with a downwardly extending web arranged against the 90 side of the web of said regular rail, said wear piece constituting a lateral extension of the head of said regular rail, bolts securing the web of the wear piece to the web of the rail, and a shim bent to fit the lateral face of said 95 regular rail and adapted to be inserted between said wear piece and said regular rail.

2. A guard rail comprising a regular rail provided with a base, a vertical web and a head and having a portion bent outwardly 100 from the main rail and forming a recess, and a wear piece arranged within said recess and secured to the side of said regular rail and constituting a lateral extension of the head thereof.

3. A guard rail comprising a regular rail provided with a base, a vertical web and a head and having a portion bent outwardly

from the main rail and forming a recess, a
wear piece arranged within said recess
against the side of the head of said regular
rail and provided with a downwardly extend-
5 ing web arranged against the side of the web
of said regular rail, and bolts securing the
web of the wear piece to the web of the rail.

In testimony whereof, we have hereunto
affixed our signatures.

CHARLES W. REINOEHL.
BENT L. WEAVER.
